US00D380554S

United States Patent [19]

Leiva et al.

[11] **Patent Number:** **Des. 380,554**[45] **Date of Patent:** *****Jul. 1, 1997**

[54] **TRANSPARENT ASSAY TESTER FOR BIOLOGICAL FLUIDS WITH A MAGNIFICATION LENS**

[75] Inventors: **William A. Leiva**, Half Moon Bay; **Ian D. Wells**, Escondido, both of Calif.

[73] Assignee: **Medix Biotech, Inc.**, San Carlos, Calif.

[*] Notice: The portion of the term of this patent subsequent to Nov. 19, 2010, has been disclaimed.

[**] Term: **14 Years**

[21] Appl. No.: **32,035**

[22] Filed: **Dec. 12, 1994**

Related U.S. Application Data

[63] Continuation-in-part of Ser. No. 15,399, Nov. 15, 1993, abandoned, which is a continuation of Ser. No. 918,340, Jul. 21, 1992, abandoned.

[51] LOC (6) Cl. **24-01**

[52] U.S. Cl. **D24/224; D24/225**

CLAIM

The ornamental design for a transparent assay tester for biological fluids with a magnification lens, as shown and described.

DESCRIPTION

FIG. 1 is a perspective view showing my new design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a front side elevational view thereof; and,

FIG. 7 is a bottom plan view thereof.
